UNITED STATES PATENT OFFICE.

DOMINA QUINTAL, OF MONTREAL, QUEBEC, CANADA. ASSIGNOR OF ONE-HALF TO
RAOUL LAURIN, OF MONTREAL, QUEBEC, CANADA.

RAILWAY SWITCH.

Application filed April 3, 1922. Serial No. 549,286.

To all whom it may concern:

Be it known that I, DOMINA QUINTAL, a British subject, residing at 3294 Letang Street, in the city of Montreal, in the Province of Quebec, in the Dominion of Canada, have invented certain new and useful Improvements in Railway Switches; and I do hereby declare that the following is a true, clear, and exact description of the same.

10 The present invention relates to improvements in a railway switch, and is fully described in the following description and illustrated in the accompanying drawings, in which:—

15 Figure 1 is a plan view of a switch according to the invention, with the switch members alining with the main line rails.

Figure 2 is a side elevation of Figure 1.

Figure 3 is a plan view with the switch 20 members alining with the switch line rails.

Figure 4 is a cross section on line 4—4 of Figure 1.

Figure 5 is a bottom plan view of one of the switch members.

25 Figure 6 is a side elevation of the cams operating the switch members, mounted on their shaft.

Figure 7 is an enlarged plan view of the quadrant operating the switch shaft.

30 Figure 8 is an end view of Figure 7.

Figure 9 is an enlarged sectional view through a portion of the switch operating mechanism casing.

Figure 10 is an enlarged plan view of the 35 locking element adapted to lock the switch.

Like numerals of reference indicate corresponding parts in each figure.

Referring to the drawings, 1 indicates the main line rails, and 2 the switch line rails.

40 Intermediate of each of said main line rails and said switch line rails there is formed a suitable longitudinal recess 3, and in the bottom wall or face of each of said recesses is formed a hole 4. The switch members 5 are suitably mounted in said recesses 3, and

45 each is provided with a pivot pin 6 adapted to engage the hole 4 in the corresponding recess 3, said switch members being provided with the usual tread surfaces 7, and longitudinal and parallel flanges 8, said tread surfaces 7 being adapted to come in alignment with the treads of either the main or the switch rails. The switch members 5 are provided at the opposite end of the pivoting

50 point with an enlarged flat portion 5^a, each

of said flat portions 5^a having a curved outer end 5^b adapted to fit in the correspondingly curved end of the main and switch rails 1 and 2. The switch members are firmly held in said recesses 3 by means of the blocks 9 60 which are rigidly secured to the main rails by the bolts 10. At their opposite ends the said members 5 are slidably held in position in said recesses 3 by means of the plates 11 which are each secured respectively to the main and switch rails 1 and 2 by the bolts 12. On the under side of each of said members 5 are located, in the flat portions 5^a, the cam recesses 13 and 14, said recesses being adapted to receive respectively the cams 15 and 16. Each cam 15 or 16 is so disposed in relation to the corresponding recess 13 or 14 as to operatively engage said recess independently, to swing said switch member 5 from one side to the other, said movement from 65 one side to the other depending on the rotation of the shaft controlling the cams. The said cams 15 and 16 are rigidly mounted in pairs on the cam shaft 17, said shaft extending outwardly on one side thereof and 70 being provided on its outwardly extending portion with a pinion 18.

Above said pinion 18 is provided a casing 19 in which there is suitably journaled a horizontal stub shaft 20. On said shaft 20 85 is mounted a quadrant 21 which meshes with the pinion 18, said quadrant being provided at its upper edge with the bevelled teeth 22 which mesh with the small quadrant 23, and 90 24 is a vertical shaft suitably journaled in the bracket 25 at one end. At its lower end shaft 24 carries said quadrant 23, and is suitably journaled in the bracket 26, said shaft 95 preferably carrying the signal light 27 and indicator 28. The edge or rim of quadrant 21 is provided adjacent the teeth 22 with preferably two holes 29, said holes being at an equal distance from the pivoting point of said quadrant and adapted to be engaged by the lug 30 projecting downwardly from the 100 locking member 31. Said locking member is provided with the vertical slot 32, and is slidably held in position between the outer side wall of the casing 19 and the partition 33, and normally pressed downwardly by means of the spiral spring 34 which abuts against the top of the casing 19 at one end and rests against the upper end of said member 31.

The casing 19 is preferably provided with 110

a keyhole 35 through which may be inserted the key 36, said key passing through the slot 32 and being adapted to lift said member 31 out of engagement with the quadrant 21 by 5 means of the lug 37 provided thereon.

In the operation of the invention, the operating lever 38 which is mounted on the shaft 20 is thrown from left to right or vice versa, and by so doing actuates the shaft 17 10 which in turn operates the cams 15 or 16 and moves the switch members 5 from the main line rail to the switch rail or from the switch rail to the main line rail. Simultaneously on operating the lever 38, the shaft 20 actuating the quadrant 21 swings the quadrant 23 from right to left thus turning the shaft 24 and indicating whether the switch is open or closed. Prior to the operation of the lever 38 the key 36 must be turned so as to 20 disengage the locking member 31, as otherwise the quadrant 21 will be prevented from movement, as well as the lever 38.

It will thus be readily seen that without the key to unlock the quadrant 21 it is absolutely impossible to operate the switch. 25

The invention above described and disclosed in the accompanying drawings is shown in one of its preferred forms, but as it is only in its experimental stage it may 30 naturally be altered from its form later on without departing from the scope of the following claims, and spirit of the invention.

What I claim as my invention is:—

1. A railway switch comprising, in combination with the main line rails and intersecting switch line rails, a pivotally mounted switch member having a cam recess; a shaft; means to operate said shaft; and means on said shaft adapted to engage said cam recess, substantially as described. 35

2. A railway switch comprising, in combination with the main line rails and intersecting switch line rails, a pivotally mounted switch member provided with two cam recesses operating in opposite directions; a shaft; means to operate said shaft; and means on said shaft adapted to engage said cam recesses, substantially as described. 45

3. A railway switch comprising, in com-

bination with the main line rails and intersecting switch line rails, a pivotally mounted switch member having cam recesses; a shaft; means to operate said shaft; cams mounted on said shaft adapted to engage each of said cam recesses; and means to lock said shaft, substantially as described. 50

4. A railway switch comprising, in combination with the main line rails and intersecting switch line rails, a pivotally mounted switch member provided with cam recesses; a shaft; means to operate said shaft; cams mounted on said shaft adapted to engage each of said cam recesses; a pinion mounted on said shaft; a stub shaft suitably journaled adjacent said shaft; a quadrant 60 65 adapted to engage said pinion; means to operate said stub shaft; and means to lock said quadrant, substantially as described.

5. In a railway switch, in combination with the main and switch tracks, a pair of 70 switch members; a switch shaft having means cooperative with the switch members to shift the same from one position to the other; an operating shaft; a gear connection between the operating shaft and the switch 75 shaft for transmitting movement from the former to the latter; and a locking device engageable with one of the gears included in said connection to prevent rotation thereof.

6. In a railway switch, in combination 80 with the main and switch tracks, a pair of switch members; a switch shaft having means cooperative with the switch members to shift the same from one position to the other; an operating shaft; gears connecting 85 the operating shaft and the switch shaft for transmitting movement from the former to the latter, one of said gears having a recessed rim; and a locking device releasably engageable with said rim to prevent rotation of said gear. 90

Signed at Montreal, Quebec, Canada, this 10th day of March, 1922.

DOMINA QUINTAL.
